UNITED STATES PATENT OFFICE

159,093

CIGARETTE SNUFFER

Kenneth D. Peach, Manhattan Beach, Calif.

Application August 8, 1949, Serial No. 4,354

Term of patent 14 years

(Cl. D85—8)

To all whom it may concern:

Be it known that I, Kenneth D. Peach, a citizen of the United States of America, residing at 317 Moonstone Street, Manhattan Beach, in the county of Los Angeles, State of California, have invented a new, original, and ornamental Design for a Cigarette Snuffer, of which the following is a specification, reference being had to the accompanying drawing, forming a part thereof.

I claim:

The ornamental design for a cigarette snuffer, as shown.

KENNETH D. PEACH.
